UNITED STATES PATENT OFFICE.

WILLIAM G. BOSWORTH, OF NEW YORK, N. Y.

FLUSHING APPARATUS.

1,361,814.

Specification of Letters Patent. Patented Dec. 14, 1920.

Application filed April 4, 1917. Serial No. 159,640.

To all whom it may concern:

Be it known that I, WILLIAM G. BOSWORTH, a citizen of the United States, and a resident of the borough of Manhattan, in the city of New York, county and State of New York, have invented certain new and useful Improvements in Flushing Apparatus, of which the following is a specification.

The invention relates to flushing apparatus and one object of the invention is to construct a siphon which will operate with little, if any, noise upon the breaking of the operation of the siphon. The short arm of the siphon extends into the water contained in the tank and the siphon is started by means of a jet of water injected into the short arm of the siphon. During the time the tank is being emptied by the operation of the siphon this jet of water continues to flow with full force into the siphon until the tank is emptied, at which time the operation of the siphon is mechanically broken by a valve or damper and the same jet of water continues to flow at full force to refill the tank and until the water within the tank has reached or nearly reached its normal high level.

Another object of the invention is to construct a valve that will permit a flushing operation to take place while a flushing tank is being lowered and which valve is constructed so that a full force of water from a supply pipe can be delivered past the valve until the water has reached its normal high level or approaches normally that mark.

The above and other objects of the invention will be more fully set forth in the following specification and claims.

As illustrating certain specific embodiments of the invention reference is made to the drawings forming a part of this specification and in which drawings,

Figure 1 is a vertical sectional elevation of a flushing apparatus embodying the invention. This figure is a view taken as on the plane indicated by the line 1-1 of Fig. 2 looking in the direction of the arrows.

Fig. 2 is a vertical sectional view taken as along the plane indicated by the broken line 2-2 of Fig. 1 looking in the direction of the arrows.

Fig. 3 is a plan view of the apparatus shown in Fig. 1 with the cover of the tank removed.

Fig. 4 is a view illustrating the damper or valve mechanism relied upon to break the operation of the siphon. In this figure the

parts are shown on a somewhat larger scale than they are shown in Figs. 1, 2 and 3.

Fig. 5 is a vertical sectional view taken as on the plane indicated by the line 5-5 of Fig. 4.

Fig. 6 is a vertical sectional view illustrating the manner in which a float engages a locking mechanism or catch so as to release a valve stem whereby it can be restored to its normal position.

Fig. 7 is a vertical sectional view of one form of valve and float construction associated therewith which can be employed in the performing of the invention.

Fig. 8 is a vertical sectional view of another form of valve and float associated therewith which can be employed in the performing of the invention.

The flushing tank is designated by 1 and may be made of any suitable material and may have any suitable cover. In this tank the water 2 is maintained at a normally high level, indicated by 3, and when the water is at this level the tank will be considered as filled. There is associated with this tank a siphon 4 having a short arm 5 that extends downwardly into the water and a long arm 6 which extends to the members to be flushed. At the rear side 7 of this tank there is provided a vertically extending recess portion 8 that is defined by or provided in the projection 9. In the construction shown this projection 9 is formed by curving the rear side 7 forwardly into the tank and the lower ends of this projection merge with or are connected to the base portion 10 of the tank whereby the tank will be watertight. The upper end of this forwardly curved or recess portion is preferably provided with a roof 11 which is above the normally high level of the water. The siphon 4 extends through this roof and a water-tight seal is provided by nuts 12 and 13 and any suitable packing which may be employed with them. All openings in the roof for the passage of pipes are sealed and located above the normal level of the water so that there will be no tendency for leakage even though the joints are not made absolutely water-tight. It is desirable to make the joints water-tight so that in case the water should rise above its normal level no leakage would take place. The tank is constructed so that in case the water rises above its normal high level the water will be discharged through the siphon, the top of which is low enough to permit the water to

75

be discharged without running over the sides of the tank. The water supply comprises pipes 14 and 15, a valve 16, pipes 17 and 18 and a nozzle or tip 19. The nozzle 19 is arranged so that when water is allowed to flow from the supply pipe a jet will be injected into the lower end of the short arm of the siphon sufficient to start the operation of the latter. When the operation of the siphon is started water is drawn from the tank so that the water flows from its high level 3 to a low level which is approximately indicated by the line 3' in Fig. 2. A float 20 is shown in its normal high elevated position in Figs. 1 and 2. As the float falls it moves along a positionable float guide 21 which normally occupies the full line position shown in Fig. 2. As the water lowers the float 20 of course drops and as it drops it engages the float return guide 22, or positioning guide as this guide may be called. The function of this positioning guide is to force the float 20 to the left (see Fig. 2) whereby the positionable float guide 21 will be moved from full normal line position to its abnormal or dotted line position, indicated in this figure. This guide 21 is free at this time to assume said abnormal or dotted position, as will hereinafter more fully appear. As the water approaches its lower level the float 20, which is preferably in the form of a ball, engages a crank 23 that is connected to a pivoted valve 24. This valve may also be referred to as a deflecting valve for the reason that it deflects the water, as will hereinafter appear. The members 23 and 24 are clearly shown in full line normal position in Fig. 4. When the float 20 has reached its lowest position, which is indicated by the dotted line 20' in Figs. 2 and 4, it will have moved the crank 23 and valve 24 to the abnormal or dotted position shown in said Fig. 4. The movement of the valve closes the lower end of the short arm of the siphon against the entrance of any further substantial amount of water. The moving of the valve to this position will consequently mechanically break or stop the operation of the siphon and there will be practically no noise resulting from this breaking or stopping, due to the fact that in the breaking or stopping of the operation of the siphon no air enters the siphon through the short arm thereof. This valve works in a bell-shaped member X at the lower end of the short arm of the siphon and this member also lends to the deadening of any noises which might result from the closing of said valve and the breaking or stopping of the operation of the siphon and the inflowing water. From the time that the operation of the siphon is started up to the time that the valve is moved to break said operation the jet of water from the nozzle or tip of the supply

is allowed to continue to flow with full force into the siphon, thereby rendering available for flushing purposes the water from the jet in addition to the water drawn from the tank, allowing the size of the tank to be reduced and hastening the flushing. As soon as the operation of the siphon is broken this jet of water impinges against the valve, is deflected into the bell-shaped member and passes through a window Y of said member directly into the tank and is the water which is supplied to refill the tank. The valve is so shaped that it will be held in its abnormal position by the impinging of the water against it. As the tank starts to refill the float moves away from the crank that operates the valve and the latter must be held in its abnormal position by means other than the float which originally moved the valve from its normal position to said abnormal position. To supply means which will maintain the valve in the abnormal position there is provided a deflecting plate 25 which is acted upon by the water from the jet with sufficient force and in such a manner as to maintain the valve in said abnormal position. Finally, as will herein-after appear, the jet of water is arrested and when this takes place the valve is automatically restored to position by its own weight, there being a counterweight 26 provided to accomplish this. A stop 25' may be provided on the bell-shaped member X to limit the movement of the valve 24, especially when the jet of water is coöperating with the deflecting plate 25 of the valve to maintain the latter in abnormal position.

The water supply has been described as comprising therein a valve 16. One form of such valve is shown in Fig. 7 and another form is shown in Fig. 8. The valve shown in Fig. 7 is the one which is illustrated as being installed in the apparatus although it will be understood that a valve like that shown in Fig. 8 could be readily substituted. The valve shown in Fig. 7 comprises a casing 27 which includes a body member 28 and a head member 29. This valve casing has any suitable inlet and outlet openings as 30 and 31, respectively, and is provided with a valve seat 32. This may be considered the main valve seat of the valve. A movable valve member 33 is shown and the particular movable valve member illustrated is of cartridge-shell shape. This movable valve member 33 slides on a tubular extension 34 which has radial openings, as at 35, and which is open at the terminal 36 whereby the full pressure of the supply is exposed against the inner head of the movable valve member 33. The open end 37 of the cartridge-shell shaped member engages the main valve seat 32 so that normal flow is prevented by the end 37 resting against the main valve seat 32. The movable valve

member is normally maintained in this closed position by the valve-stem 38 which is maintained in its normal position by pressure of a spring 39 that is strong enough to oppose the pressure of the water, and also to maintain the main valve tight. A pivoted strut 40 is in front of the valve member 33 and as the valve-stem 38 is moved from its normal position to an abnormal or retracted position the notched free end of the strut 40 will hold the movable valve member 33 substantially closed. This valve will stay substantially closed for the reason that the movable member 33 can move only a short or limited distance away from the valve seat 32 due to the strut 40. This construction consequently holds in closed position what may be considered to be the movable member of an auxiliary valve. The auxiliary valve comprises the interior barrel of the shell-shaped member 33 that engages the exterior of the tubular extension 34 and covers the radial opening 35 when the barrel member is thus held. In other words, the auxiliary valve may be considered as a cylindrical valve construction because the openings 35 still remain covered by the shell-shaped member. As the valve-stem 38 approaches the end of its movement toward the abnormal or full retracted position a shoulder 41 engages a cam 40' on the pivoted strut 40 so that the notched end of said strut is moved out of engagement with the movable valve member 33 whereby the pressure of the water will force the movable valve member 33 forwardly to its abnormal or full open position, or in other words to a position where the water can flow directly from the openings 35 into the interior of the casing from whence the water flows through the discharge or outlet opening 31. The valve-stem 38 may be considered a part of a valve operating mechanism and this valve operating mechanism or the valve-stem thereof is maintained in its abnormal or retracted position by a locking mechanism or catch 42, which locking mechanism or catch is pressed by a spring 43 which is secured to the casing by bolts 44 and which catch enters a slot 45 of the stem. As long as the catch 42 remains in the slot 45 the valve-stem 38 is held in retracted position. When the valve-stem 38 is in its normal position a lug 46 thereupon engages the upper end of the positionable float guide 21 and holds the latter in its normal position. When, however, the valve-stem 38 is in its retracted position this lug 46 occupies the position indicated by 46' and the positionable float guide 21 is then free to move from the full line to the dotted line position shown in Fig. 7. This movement is accomplished by the float 20 moving downwardly along the positioning or return guide 22 that is on the casing so that by the time the float 20 reaches the dotted position shown in Fig. 7 the positionable float guide 21 will be in its abnormal or dotted position, as indicated by 21'. It will here be noted that the lower end of the positionable float guide 21 is held so that it can swing, 70 due to the ball and socket connection clearly shown in Fig. 4 and indicated in Figs. 1 and 2. As the water rises in the tank, thus lifting the float 20, the float will finally occupy the broken line or dotted position indicated by 21'' and when in this position the collar or wearing plate 21^a on the float will engage depending flanges 42^a and 42^b of the catch 42, thus lifting the catch out of the notch whereby the spring 39 will restore the valve-stem 38 to its normal position. As the valve-stem 38 is restored to its normal position the lug 46 will restore the positionable float guide 21 to its normal or full line position and the valve-stem 38 will also force 80 the movable valve member 33 to its normal position and the rest of the members in the valve will all be automatically restored to their normal positions. The form of valve shown in Fig. 8 has a casing 47 which comprises members 48 and 49. An inlet opening is designated by 50 and an outlet opening is designated by 51. The casing has a diaphragm which provides a valve seat 52. This valve seat may be considered to be 95 made up of a main valve seating portion 53 and an auxiliary valve seating portion 54. A main movable valve member 55 can be moved by a valve-stem 56 against the pressure of the water so as to open the valve 100 and permit a full flow of water through the casing, provided an auxiliary member 57 is moved from its substantially seated position. A yoke 58 has longitudinally extending legs 59 the free ends of which are secured to the 105 casing member 48. One end of a spring 60 engages a cross member 61 of this yoke 58 and the other end of this spring engages the valve-stem 56 so as to normally tend to force the movable main valve member 55 to closed or seated position. The cross member of the yoke is also engaged by one end of a spring 62 the other end of which spring presses against the auxiliary valve member 57 tending to continuously force this auxiliary valve member 57 to closed position. The free notched end of a strut 63 which is pivotally mounted upon the casing at or by means of a member 64 normally engages the auxiliary valve member 57. This valve 115 member 57 is mounted upon the valve-stem 56. As soon as the main valve member 55 is forced from its normal seating position it allows the incoming water to press on the rear side of the auxiliary valve member 57 120 in a manner to tend to force the auxiliary valve member forwardly off of its seat and the spring 62 is not itself strong enough to maintain the auxiliary valve member on its seat against the pressure of the water. The 125 130

strut 63 has therefore been provided to maintain the valve member 57 in substantially closed position until it is desired to release this valve member 57 whereby the full supply 5 of water can pass through the valve casing. The release of the auxiliary valve member 57 is accomplished by a member 65 on the valve-stem 56 engaging a cam portion 63' that is on the strut 63 whereby said strut 10 will be lifted from its engagement with the auxiliary valve member 57. Immediately upon or before the release of this auxiliary valve member a locking means 66 is brought into a position to hold the valve-stem in its 15 normal or full retracted position. This locking means or catch 66 enters the slotted portion 68 of the stem to accomplish this function. This catch has a counter-weight 69 for forcing it into the notched portion 20 as soon as the latter is in position which will permit the locking action to take place. The valve-stem 56 has a lug 70 for moving the positionable float guide from an abnormal or dotted position 21^x to a normal full 25 line position 21^y and for holding the guide in its normal position. It can also be relied upon to prevent turning of the valve-stem 56. There is secured to the casing a return float guide or positioning guide 22^x that 30 causes the positionable float guide 21 to be moved from its normal position to abnormal position as the float falls in a manner which will be obvious from an inspection of Fig. 8, especially in view of what has preceded 35 in connection with a description of the member which performs the same function in Fig. 7. The float may be made of any suitable material, as glass or metal, is air-tight and is preferably in the form of a ball having 40 a tubular portion extending through it. which tubular portion is the part which directly engages the positionable float guide 21. A filler washer—or washers—, such as 67, is provided at the top of the ball to furnish 45 the member which directly engages the ends of the depending members 42^a and 42^b, clearly shown in Fig. 6.

It will be observed that the movable valve member shown in Fig. 7 is opened by the pressure 50 of the water and is held in closed position solely by the pressure of the spring 39 which forces the stem 38 against the movable member 33 in a manner and with sufficient force to maintain the valve closed, even 55 against the pressure of the water. In the valve construction shown in Fig. 8 the valve is opened by moving the main or movable valve member 55 against the head of the water. When the valve is in closed position 60 the water assists in maintaining the valve member 55 against its seat and consequently the spring 60 of the valve shown in Fig. 8 need not be as strong as the spring 39 of the valve shown in Fig. 7. The valves 65 shown in Figs. 7 and 8 when installed in the

apparatus illustrated operate in substantially the same manner. The stem 56 shown in Fig. 8 may be considered as a part of the valve operating means and the means 66 shown in Fig. 8 may be considered as a 70 means for locking the valve operating mechanism when in one position.

In the apparatus illustrated in Figs. 1, 2 and 3 the valve 16 is of the form shown in Fig. 7 and in order that the valve may be 75 opened by a pushing movement instead of a pulling movement there is provided as a part of the valve operating mechanism a lever 71 which is fulcrumed at 72 on a member 73 which is secured to the tank in 80 any suitable manner. One end 74 of this lever is pivotally connected to the valve-stem 38 at 75 and the other end 76 of the lever is pivotally connected to a push button 78 at 79. If a valve of the type shown in 85 Fig. 8 were employed the push button could be secured directly to the valve stem 56 and the employment of the lever could be omitted.

The flushing operation may be performed 90 substantially as follows: The button 78 is pushed so as to actuate the valve operating mechanism whereby a full opening of the valve 16 can be effected and when in this position the valve operating mechanism or 95 stem thereof is locked or caught by the locking mechanism or catch. While the valve is closed, or in other words, when the movable parts thereof are in a normal position, a lug on the stem maintains the positionable 10 float guide 21 in a normal position out of engagement with said locking means. When, however, the valve-stem is moved to its abnormal or retracted position the construction is such that this positionable float 10 guide is free to be moved from its normal position to its abnormal position, whereby it can control the movement of the float to its high abnormal position so that the float 11 will effect an unlocking or release of the valve operating means or valve-stem thereof and permit the return of the valve-stem and the parts associated therewith to their normal positions. When the valve is opened a jet of water flows from the nozzle or tip 19 at the end of the supply pipe into the short arm of the siphon starting the operation of the siphon. The starting of the operation of the siphon causes the water within the tank to be lowered, this taking place while 12 the jet from the water supply continues to flow with full force into the short arm of the siphon. As the water in the tank approaches its lower level the float 20 engages the crank 23 gradually moving the pivoted 12 valve 24 from its normal full line position shown in Fig. 4 to its abnormal or dotted position shown in said figure, the dotted line position being the position which this member occupies when the water has 13

reached its lowest level in the tank; in other words, when the tank is to be considered as having been emptied. As the valve 24 comes into said abnormal position it gradually 5 breaks or stops the operation of the siphon and the water discharged from the tip or nozzle 19 is finally deflected into the bell-shaped member at the end of the siphon and ultimately into the tank. During the initial 10 movement of the valve 24, from its normal to its abnormal position, it closes the opening at the lower end of the short arm of the siphon, thus gradually decreasing the flow 15 of water through the siphon as above indicated.

The decrease of flow of water from the siphon of the flushing apparatus stops the siphonic action within the bowl—for which the flushing apparatus is particularly designed and intended to be used—while there 20 yet remains a sufficient supply of water passing through the siphon of the flushing apparatus to refill or seal the bowl after the siphonic action within the bowl has been 25 broken. The reduced flow through the siphon of the flushing apparatus continues until the valve 24 has been moved to its abnormal position where it serves to deflect the water from the tip or nozzle 19 into the 30 bell-shaped member and ultimately into the tank. As the water starts to rise in the tank the float 20 disengages the crank 23 and the valve remains in place in said abnormal position as long as the jet of water continues to flow from the nozzle 19.

The main valve is moved or opened far enough by hand to be caught or locked before the secondary or auxiliary valve can be released. This prevents flushing until the 40 main valve is caught; otherwise, the tank might be emptied and if the main valve had not been opened far enough to be caught the tank would not be refilled. The valve construction is such as to allow practically the 45 full force of water to be injected into the siphon. This gives a quick start and makes the discharge of water from the siphon much more rapid than with the ordinary valve. Due to this construction the same or 50 better results are obtainable than by using what is known at the present time as a high tank, for flushing purposes.

As has been pointed out the positionable float guide 21 has been moved from its normal 55 position to its abnormal position; in other words, to a position in which it can effect a release of the means which locks the valve operating mechanism in a retracted or abnormal position. The rising of the water 60 in the tank with the positionable float guide 21 in its abnormal position causes the float to ultimately engage said locking means whereby the release of the valve operating mechanism is effected, thus causing a closing of 65 the valve and a shutting off of the flow of

water which is passing through the supply pipe, and the return of the valve stem due to the engagement of the lug thereupon with the positionable float guide restores the latter to its normal position. When this takes 70 place the valve 24 is moved from its abnormal or dotted line position shown in Fig. 4 to its full line position due to the counter-weight 26 and the parts are in position and ready for performing another flushing operation on the opening of the valve in the water supply.

It will be noted that many features of the present invention are applicable to and can be used in or with tanks heretofore used; for 80 instance, in a tank in which the long arm of the siphon passes through the bottom of the tank. While push-buttons have been shown as a part of the means for operating the valves, still it will be manifest that chains 85 or other appliances may be used for operating the valves; for example, where the improved form of valve is used on high tanks.

If, for any reason, the valve 16 should fail to operate properly, due for instance to too 90 great pressure of the water within the supply pipe 14, it will be manifest that the pressure of the water flowing through this pipe can be readily reduced, as by the introduction of a hand valve T that will throttle the 95 passageway through the pipe. This valve thus introduced into the pipe could be employed to shut off the water from the flushing system, if such were desired, in order to facilitate repairs.

The improvements herein set forth are not limited to the precise construction and arrangement shown and described for they may be embodied in various forms and modifications without departing from the spirit 105 and scope of the invention.

What I claim and desire to secure by Letters Patent of the United States is:

1. A flushing apparatus of the class described comprising in combination a tank, a 110 siphon having the short arm thereof extending downwardly into said tank, a water supply pipe having at the end thereof a tip or nozzle arranged to project a jet of water into the short arm of the siphon for starting 115 and supplying water to the latter, a valve in said supply pipe which is opened by hand and means by which said valve is caused to remain open until automatically allowed to close, a deflecting valve arranged to close the short arm of the siphon when the valve is in an abnormal position, whereby the operation of the siphon will be broken, and cause the water from said jet to enter the tank instead of the siphon, a crank connected to said 120 deflecting valve, and a float arranged to operate with said hand-operated valve and said crank so that as the float approaches its lowest position it will engage the crank and move the deflecting valve from its normal 125 130

position to said abnormal position and so that as the float approaches its upper position it will cause a closing of the valve previously opened by hand.

- 5 2. In combination a tank, a siphon having a short arm thereof extending downwardly into the water within the tank, a valve, means for directing a jet of water into the lower end of the short arm of said siphon 10 when the said valve is in its normal position, said valve being constructed so that when moved from its normal position to an abnormal position it will close the lower end of said short arm while still sealed with the 15 water in the tank and by said closing will stop the operation of the siphon, the construction also being such that said valve will be held in place in said abnormal position by the jet of water being projected against it 20 until said jet is interrupted, after which the valve is automatically restored to its normal position.

3. In combination a siphon, a water-supply pipe having a tip or nozzle for projecting a jet of water into said siphon, a valve 25 movable upwardly into position to break the operation of the siphon and for deflecting the water of said jet and constructed so that it is held in said elevated position by said 30 jet, the construction of said valve also being such that upon said jet being stopped said valve will drop from said elevated position, due to its own weight.

4. In a device of the class described, in 35 combination a siphon having at the short end thereof a bell-shaped member, a supply pipe having a tip or nozzle for directing a jet of water into the siphon in a manner to start the siphon, a deflecting valve 40 in said bell-shaped member which in its normal position permits the jet to be directed from the tip or nozzle into said siphon and which valve is constructed so that it can be moved to an abnormal position 45 to stop the operation of the siphon and to prevent the water from the jet entering the siphon.

5. A tank having in combination therewith a siphon the short arm of which extends downwardly into the tank, the long arm of which extends downwardly below the bottom of the tank, the top of the siphon being below the lowest unsealed opening in the tank and extending through 55 an opening in one of the walls of the tank, which opening is sealed but above the top of the upper normal water level within the tank, and means whereby the siphon will be started so as to withdraw water from the 60 tank and for thereafter refilling the tank with water to its normal level.

6. A tank having a vertically extending portion of the rear wall thereof curving forwardly into the tank and a roof portion covering the top of said curved por-

tion, the lower part of said curved portion being integral with or connected with the base of the tank, and in combination with said tank a siphon with the short arm thereof arranged to extend into water within 70 the tank, the siphon extending through said roof so that the long arm thereof will pass through the vertically extending cavity provided in the forwardly extending curved portion and out of contact with water in 75 the tank.

7. An apparatus of the class described comprising in combination a tank, a siphon having the short arm thereof extending into the water in said tank, a supply pipe having a member arranged to direct a jet of water into the siphon in a manner to start the operation thereof when the tank is filled, a valve which can be opened by hand whereby said jet will be started, means for 80 holding said valve open until the tank is emptied and until the tank is again filled or nearly so, a pivoted valve, a float and means whereby when said float approaches its lowest position as the water falls in the 85 tank said pivoted valve will be moved to its abnormal position whereby the operation of the siphon will be broken and the jet of water will be deflected into the tank, means for guiding the float so that as said 90 float moves upwardly it can release the hand-operated valve whereby the latter can be automatically closed.

8. A device of the class described having in combination a flushing tank, a water-supply pipe having a valve, means for discharging water from said tank when the valve in the water-supply pipe is opened, mechanism for locking said valve in open position during the fall of water within 100 the tank, a float, positionable means for guiding said float which means can be moved to an abnormal position when the valve is opened whereby the float is moved from its normal position to its abnormal 105 position, a return or positioning guide engaged by said float which return guide effects a moving of the positionable float guide to its abnormal position as the float moves downwardly with the fall of the 110 water, means actuated by said float for preventing a further discharge from the tank, said float being positioned by the positionable float guide as the water rises whereby 115 said float actuates the mechanism which locks the valve in its open position thus allowing an automatic closing of the valve.

9. In combination in a flushing tank, a siphon having the short arm thereof extending downwardly into the water within said 120 tank, a water-supply pipe having a tip or nozzle for directing water into the lower end of the short arm of the siphon so as to start the siphon, a hand-operated valve in said supply-pipe for permitting the flow 125

of water from said tip or nozzle to said siphon, a valve for deflecting the jet from the nozzle, a crank connected thereto, a float, a positionable float guide which float 5 guide is associated with a member of said first named valve so that the closing of said valve will move the said float guide from its abnormal to its normal position, means for holding the valve open until released 10 by the float, a return or positioning guide for moving the positionable float guide to abnormal position, the float guide being arranged so that the fall of the water in the tank will cause the float to engage the crank 15 of the said deflecting valve whereby said valve will be moved to a position to break the operation of the siphon, the construction of said valve being such that said valve will remain in said last-mentioned position 20 until the tank is filled, the positionable float guide being arranged so that when in its abnormal position the raising of the float will cause a releasing of the means which holds the valve in the water-supply pipe 25 open.

10. In a device of the class described in combination a flushing tank having therein a siphon with a short arm of the siphon extending into the water within the tank, a 30 water supply pipe having a tip or nozzle arranged to direct a jet of water into the lower end of the short arm of said siphon so as to start the operation of the siphon, a normally closed spring-pressed valve having valve operating means which can be moved from its normal position in which the valve is closed to an abnormal position for opening the valve, a locking means for engaging said valve operating means and 40 for holding said valve operating means in abnormal position until released, a float and a positionable float guide held in normal position by said valve operating means which guide is automatically moved to abnormal 45 position by the float after the float starts to fall and prior to the float reaching an elevated abnormal position, means for guiding the float whereby said position of the positionable float guide can be effected, a movable valve and crank connected thereto, which movable valve can be moved from a 50 normal to an abnormal position by the float as the water in the tank reaches a low level, whereby in said abnormal position the valve 55 will break the operation of the siphon and will deflect the water delivered from the tip or nozzle into the tank so that the water in the tank can be restored to its normal elevated position, the construction being 60 such that as the float rises to its elevated abnormal position it will automatically cause the release of the locking means so that the valve operating means will move the movable valve member to its normal 65 or closed position and whereby the float and

the positionable float guide will be restored to their normal positions.

11. A flushing device having a tank, a siphon through which water is withdrawn from said tank, the short arm of which siphon is provided with a valve that is under the control of the water in the tank and which valve operates so as to stop the siphonic action before the falling water in the tank reaches the lower end of the short 75 arm of the siphon.

12. A flushing device having a tank, and a siphon through which water is withdrawn from said tank, the short arm of which siphon is provided with a valve that is under the control of water in the tank and which valve operates to stop the siphonic 80 action before air can enter the lower end of the short arm of the siphon.

13. A flushing device of the class described having a siphon, a valve at the entrance end of the short arm of the siphon, and means for controlling the position of said valve, whereby the same will be closed prior to the surface of the water reaching 90 the lower end of the short arm of the siphon and break the operation of the siphon.

14. A device of the class described comprising in combination a tank or receptacle for holding water, a siphon for withdrawing the water from the tank, a valve provided for the short arm of the siphon, and means under the control of the falling water within the tank for mechanically moving the valve so that the flow through the siphon 100 will be restricted, to thereby break the siphonic action prior to the upper surface of the water reaching the lower end of the short arm of the siphon.

15. A device of the class described comprising in combination a tank, a siphon through which water is withdrawn from said tank, a valve for the short arm of said siphon, and a float for moving, during its downward movement, the valve toward closed position, the construction being such that the valve substantially closes the entrance end of the short arm against the entrance of any substantial amount of water whereby the valve can stop the action of the 110 siphon before the top of the filling water within the tank reaches a position where air can enter the short arm of the siphon.

16. A flushing device having a tank, a siphon through which water is withdrawn 120 from the tank, and a valve co-operating with one arm of the siphon to stop the operation of the siphon before air can enter the said arm.

This specification signed and witnessed 125 this 2nd day of April, A. D. 1917.

WILLIAM G. BOSWORTH,
Signed in the presence of—
EDWIN A. PACKARD,
HENRY T. HORNDIDGE.

It is hereby certified that in Letters Patent No. 1,361,814, granted December 14, 1920, upon the application of William G. Bosworth, of New York, N. Y., for an improvement in "Flushing Apparatus," an error appears in the printed specification requiring correction as follows: Page 7, line 74, claim 11, for the word "simponic" read *syphonic*; and that the said Letters Patent should be read with this correction therein that the same may conform to the record of the case in the Patent Office.

Signed and sealed this 25th day of January, A. D., 1921.

[SEAL.]

L. B. MANN,

Acting Commissioner of Patents.

Cl. 4—5.
